COMBINATION LAMP AND TELEVISION ANTENNA

Clarence Baker Story, Savage, Md., assignor of
one-half to Joseph Kolodny, Baltimore, Md.

Application January 12, 1953, Serial No. 23,095

Term of patent 7 years

(Cl. D48—20)

To all whom it may concern:

Be it known that I, Clarence Baker Story, a citizen of the United States of America, residing at Savage, in the county of Howard, State of Maryland, have invented a new, original, and ornamental Design for a Combination Lamp and Television Antenna, of which the following is a specification, reference being had to the accompanying drawing, forming a part thereof:

Figure 1 is a front elevational view of a combination lamp and television antenna embodying my new design;

Figure 2 is a side elevational view thereof;

Figure 3 is a top plan view of the same, and

Figure 4 is a sectional view on the line 4—4 of Figure 1.

The dominant features of my design are shown in solid lines.

I claim:

The ornamental design for a combination lamp and television antenna, as shown and described.

CLARENCE BAKER STORY.
